METHOD FOR CHARGING COMPOSITIONS,
INCLUDING A VOLATILE PROPELLANT IN
PRESSURE-TIGHT CONTAINERS

Douglas M. McBean, Rochester, N. Y., and Leo J. De Costa, Rutherford, N. J., assignors, by mesne assignments, to Carter Products, Inc., New York, N. Y., a corporation of Maryland

Application December 8, 1949, Serial No. 131,801

1 Claim. (Cl. 226—100)

1
This invention relates to the filling of fluids, including volatile propellants and aqueous liquids, into pressure-tight containers.

In the packaging of materials including volatile propellants in pressure-tight containers, it has heretofore been customary to fill and close the container at atmospheric pressure, keeping the temperature of the materials to be packaged below a temperature at which the vapor pressure of the propellant is greater than the prevailing atmospheric pressure. When the product to be packaged comprises or includes water or an aqueous solution or suspension, filling at low temperature is unsatisfactory because the temperature required to maintain the useful propellants in liquid phase at atmospheric pressure is below the freezing temperature of the product or the water or aqueous solution therein. Thus, in filling at temperatures low enough to keep the useful propellants in liquid phase the product freezes and mixing of the product and the propellant is prevented. The container must therefore be subsequently heated and agitated in order that a proper mixing of the product and propellant be accomplished. This procedure is unsatisfactory both because of the time involved in accomplishing mixing by heating and agitating the container and because of the fact that, despite the heating and agitation, a satisfactory mixing is not uniformly accomplished.

By a volatile propellant we mean a compound having a vapor pressure appreciably above atmospheric pressure at normal room temperature. A number of such compounds are disclosed in co-pending application Serial No. 125,032, filed on November 2, 1949. Such compounds may be used and are satisfactory for propelling a liquid product of the type contemplated by this invention from its container.

It is the object of the present invention to provide an improved and economical method for charging an aqueous product and a volatile propellant into a pressure-tight container without resorting to refrigeration and without resorting to the procedure set forth above for mixing the contents of the filled container subsequent to the filling operation. In general our improved method comprises the steps of introducing a measured charge of volatile propellant in liquid phase into a charging chamber, connecting the charging chamber to a packaging container having a measured charge of aqueous product therein and supplying to the charging chamber propellant in gaseous phase at a constant pressure above the vapor pressure of the liquid propellant at the prevailing temperature, preferably room temperature, whereby all of the charge of liquid propellant is forced from the charging chamber

2
into the packaging container and the filling passages leading to the interior of the packaging container are cleared of liquid propellant.

For a more detailed description of the method of our invention, reference may be made to the accompanying drawing in which the single figure diagrammatically sets forth, in elevation and partly in section, one type of apparatus by which the method may be accomplished.

10 In the drawing a typical packaging and pressure-tight container is illustrated in section as having a body portion 1 and a suitably attached concave bottom wall 2. An outlet valve is suitably secured in an opening in the top wall of the 15 can by a pressure-tight seal or connection. The valve shown comprises a tube 3 having an in-turned flange 4 at its inner end which forms a valve seat. A valve plug 5, carried by a valve stem 6, is resiliently held in engagement with the 20 valve seat 4 by a spring 7 which is compressed between the flange 4 and a stop 8 struck from the stem 6. Within the can is contained an aqueous liquid product 9 which will comprise approximately 80 to 90 per cent of the contents of the 25 filled packaging container. Such an aqueous product may be of the type disclosed in the co-pending application Serial No. 125,032, referred to above. A tube 10 of suitable material is fitted over the lower end of tube 3 within the can or 30 packaging container and extends to a point near the juncture of the side and bottom walls 1 and 2 of the container. Such a positioning of the lower end of tube 10 assures expulsion of substantially all of the contents of the filled can when 35 it is used.

35 A charging chamber 11, having a tube-like outlet 12 at its lower end in which there is a valve 13, is located above the can or packaging container. A gasket 14 is supported at the lower 40 end of outlet 12 beyond valve 13, the lower surface of the gasket being adapted to receive the upper edge of tube 3 of the container in a pressure-tight connection. A spider 15 is secured to the inner lower end of outlet 12 and has depending from it a valve-operating member 16, the lower end of which is adapted to engage the upper end of valve stem 6 when tube 3 of the 45 can is brought into engagement with the gasket 14. The gasket 14 is provided, on its lower surface, with a bevelled recess 17 surrounding and concentric with its central opening to assure a proper seating of the tube on the gasket so that valve-operating member 16 will engage valve stem 6 to open the valve when tube 3 is seated on 50 the gasket.

55 One satisfactory means for bringing the packaging container into position so that its valve tube 3 is connected to the outlet 12 of the charg-

ing chamber, through gasket 14, is a table 18. The table 18, on which the container may be placed, is movable up and down by means of a hydraulic lift or other type of support.

A supply container 19 for liquid propellant 20 is connected to the charging chamber 11 through a conduit 21 having therein a valve 22, for instance a check valve, a metering device 23, and a conduit 24 also having therein a valve 25, for example a check valve. The metering device 23 comprises a cylinder and a reciprocable piston 26 adapted to be reciprocated by a piston rod 27. When piston 26 is retracted in the cylinder, check valve 22 opens and a measured quantity of liquid propellant enters the cylinder. When the piston 26 is urged forward in the cylinder, check valve 22 closes and check valve 25 opens, permitting the flow of the measured quantity of the liquid propellant to the charging chamber 11.

A cylinder or container 28 of propellant is provided with a valve 29 and pressure gauge 30 on its outlet fixture 31 and is connected to the upper end of charging chamber 11 through conduit 32 in which there is a valve 33 for controlling the flow of gaseous propellant through the conduit. Cylinder 28 is supported in a liquid bath 35. An electric heating element 36 extends into the liquid bath to heat the liquid and thereby the cylinder 28 and its contents. The circuit of the heating element 36 is controlled by a switch 37 which is responsive to the temperature of the liquid bath by means of a thermocouple or thermometer 38. By these means the contents of the container 28 may be kept at such temperatures that the pressure thereof may be maintained constant.

In using the above-described apparatus for carrying out the method of our invention, a supply of liquid propellant is maintained in container 19. The pressure acting upon the liquid propellant is the vapor pressure of the propellant at the prevailing temperature. One suitable propellant that has been used has a vapor pressure of about 40 p. s. i. gauge at room temperature, that is, at about 70 to 72° F. The propellant in gaseous phase in cylinder or container 28, which may be either the same propellant as is in container 19 or a suitably chosen similar one, in this case would be maintained at such a temperature that it would be under a pressure of approximately 40 to 80 p. s. i. gauge.

The method of this invention, as carried out by the described apparatus, is as follows: Piston 26 is retracted and the metering cylinder is thereby filled with a measured quantity of liquid propellant 20 entering the cylinder through conduit 21 and check valve 22. The piston 26 is then moved forward in the cylinder, forcing the measured quantity of liquid propellant through the conduit 24 and valve 25 to the charging chamber 11, check valve 22 closing to prevent the return flow of propellant from the cylinder to container 19. With the charging chamber thus loaded with a measured quantity of liquid propellant, a container in which there has been introduced in any desired manner a measured quantity of aqueous product is connected to the lower end of outlet 12 through gasket 14, the valve of the container being thereby opened. Valves 13 and 33, which have previously been closed, are then opened, preferably simultaneously but not necessarily so. Upon the opening of valve 33, propellant in gaseous phase enters the chamber 11 above the liquid level of propellant 20 contained therein. The pressure

of the propellant in gaseous phase being maintained by the liquid bath 35 and heater 36 at a substantially higher pressure than the vapor pressure of the liquid propellant at the prevailing temperature, forces liquid propellant through valve 13, outlet 12, valve 3 of the container, and tube 10 thereof into the container at a point below the liquid level of the aqueous product therein. This mixes the propellant with the product during introduction of the propellant. Valves 13 and 33 are maintained open until the pressure of the mixture of aqueous product and liquid propellant in the packaging container is equal to the pressure of the propellant in gaseous phase supplied from the cylinder 28. The valves 13 and 33 are then closed and the container withdrawn from outlet 12, the valve 3 in the container closing upon withdrawal of the container because of the pressure within the container. The pressure within the container thus is equal to the pressure of the gas propellant in cylinder 28.

By this method containers may be rapidly filled to uniform pressures with uniform and intimately mixed quantities of aqueous products and volatile propellants. Additionally, by this method the only loss of propellant is of the small amount in gaseous phase remaining in the lower end of outlet tube 12. If the propellant were introduced in liquid phase only, a considerably greater loss would occur because the volume of liquid propellant remaining in the filling or outlet tube 12 would represent a substantial portion of the charge of propellant introduced into the product container. Also in the latter case a certain amount of liquid propellant might remain in the tube 3 of the container valve and in the upper end of tube 10, thereby possibly causing the valve to freeze closed and causing the first material subsequently propelled from the container to be a shot made up primarily of liquid propellant.

We claim:

The method of charging a pressure packaging container, having a measured charge of an aqueous product therein, with a volatile propellant which comprises the steps of introducing a measured charge of volatile propellant in liquid phase to a charging chamber under a precharging pressure at least as great as the vapor pressure of the propellant at the prevailing temperature, connecting the bottom of the charging chamber to the packaging container at a point below the level of the aqueous product therein, and simultaneously supplying to the charging chamber above the liquid level therein propellant in gaseous phase at a constant pressure above the precharging pressure whereby all of the charge of liquid propellant is forced into the packaging container, the propellant in gaseous phase being maintained at said constant pressure by being maintained at a temperature substantially above said prevailing temperature.
